US00D841029S

(12) **United States Design Patent** (10) Patent No.: **US D841,029 S**
(45) Date of Patent: **** Feb. 19, 2019**

(54) **DISPLAY SCREEN OR PORTION THEREOF
WITH GRAPHICAL USER INTERFACE**

- (71) Applicant: **Apple Inc.**, Cupertino, CA (US)
(72) Inventor: **Stephen O. Lemay**, San Francisco, CA (US)
(73) Assignee: **Apple Inc.**, Cupertino, CA (US)
(**) Term: **15 Years**
(21) Appl. No.: **29/577,009**
(22) Filed: **Sep. 8, 2016**

CLAIM

The ornamental design for a display screen or portion thereof with graphical user interface, as shown and described.

DESCRIPTION

The FIGURE is a front view of a display screen or portion thereof with graphical user interface showing the claimed design.

The dot-dash broken lines in the FIGURE and the areas within the dot-dash lines show portions of the graphical user interface that form no part of the claimed design.

The outermost dashed broken lines in the FIGURE show a display screen or portion thereof, and form no part of the claimed design. The other dashed broken lines in the FIGURE show portions of the graphical user interface that form no part of the claimed design.

1 Claim, 1 Drawing Sheet
